UNITED STATES PATENT OFFICE.

JASON H. GREENSTREET, OF INDIANAPOLIS, INDIANA, ASSIGNOR, BY MESNE ASSIGNMENTS, TO WIREBOUNDS CORPORATION, A CORPORATION OF MAINE.

BOX-MACHINE.

1,325,718.

Specification of Letters Patent. Patented Dec. 23, 1919.

Application filed December 5, 1911. Serial No. 664,116.

To all whom it may concern:

Be it known that I, JASON H. GREENSTREET, a citizen of the United States, residing at Indianapolis, in the county of Marion 5 and State of Indiana, have invented a new and useful Box-Machine, of which the following is a specification.

My invention relates to the class of machines employed in making wirebound 10 boxes, blanks or parts, or sides for boxes and crates, by the action of stapling or other fastener-setting mechanism upon assembled box materials progressively subjected to the operation of said mechanism.

15 Among other objects the invention is intended to provide an improved machine of this class having work-controlled means for automatically interrupting the stapling or fastener-setting operation at given places in 20 or between parts of the work; for instance, at the box joints or ends of the cleats and in spaces between consecutive box blank assemblies.

Another feature of the invention is the 25 provision of automatic gage means for initially positioning the work relative to the fastener-setting mechanism, and by which successive blanks may be automatically spaced.

30 The nature of the invention will be best understood from the following description with reference to one form of machine embodying the invention which is shown for illustration in the accompanying drawings:

35 In said drawings:

Figure 1 is a plan view of a wirebound box blank machine containing one embodiment of my invention, this view omitting the usual binding wire applying and stapling 40 mechanism of such machine.

Fig. 2 is a longitudinal vertical section on a smaller scale, showing one unit of the binding wire applying and stapling mechanism.

45 Fig. 3 is a fragmentary section, in substantially the same plane as Fig. 2, showing automatic gage means.

Fig. 4 is a cross-section on the line 4—4 of Fig. 3.

50 The drawings illustrate a machine, similar in general type to that disclosed in my prior Patent No. 985,996, dated March 7, 1911, wherein box cleats and superposed sheet material for the box sides are advanced

step-by-step beneath a gang of binding wire 55 applying and stapling mechanisms, of which one unit is shown in Fig. 2, for stitching, so to speak, the sheet material, cleats and binding wires together; the binding wires being led from any suitable source of supply and drawn with the work beneath the staplers in a manner well understood in the art. Fig. 1 of the drawings shows the box cleats, which are designated by the numeral 27, but omits the sheet material intended to be placed thereupon. 65

In this illustrative type of machine the cleats 27 are fed in longitudinal guides across a work table or anvil 12, above which are arranged the staplers 13. The cleats are 70 fed by preliminary feed chains 10 driven by a friction driving train evenly or continuously at a normal speed exceeding the speed of the primary feed chains 11. Said primary feed chains are arranged beyond the 75 stapling plane and are driven by any suitable means, for instance by the shaft 16, gears 17, ratchet arm 18 and pitman 19 on the main shaft 20, and are caused to have an intermittent action alternating with the action of the staplers, in a common and well known manner; the primary feed chains engaging the cleats, or the material of the box blank, after the same has passed the stapling plane and thereby causing a step-by-step 85 feed of the work beneath the staplers, which latter operate upon the work during its intervals of rest.

While in my said prior patent I disclosed separate spacing means for interposition between the cleats, I have omitted such disclosure from the present illustration because the particular form of cleats illustrated, which are of the character described in patent to Greenstreet, No. 1,115,066 dated 90 October 27, 1914, are provided with integral portions (intended to be subsequently detached) by which the cleats pushed one behind the other by the preliminary feed means are self spaced apart, as is clearly 95 shown at the left of Fig. 3.

The staplers 13, of which there should be as many as there are binding wires to be stapled to the box blank materials, may if desired be any ordinary type of combined 100 staple formers and drivers, such as are usually employed in wirebound box blank machines, adapted at every operation to form

staples from staple stock wire and to drive the same into the work. In the drawings I have represented diagrammatically a common type of staple forming and driving mechanism, having provision for interruption of its stapling action by depriving it of staple wire feed or intercepting the supply of a staple to the former and driver. In this form of mechanism, which is of the general type shown in my said prior Patent No. 985,996, the actuation of the staple former and driver by the vertically reciprocating bar A, sometimes called the upper "stitcher bar", also actuates a vertically reciprocatory plunger 14, for operating a feed pawl 14', which engages a ratchet wheel R on one of the staple wire feed rolls S; whereby the reciprocation of said plunger causes intermittent feed of the staple wire, thus at every operation supplying sufficient stock for formation of a staple. Usually, as in this case, the staple wire is fed on the up stroke of the actuating bar, and the staple formed thereupon is driven upon the ensuing down stroke.

Said plunger 14, which is carried by a bracket *a* on the actuating bar A and is yieldingly held in relation thereto by a spring surrounding the plunger, is provided at its upper end with a head 14', under which a bar 15 carried by swinging arms 15' may be swung to engage said head and interrupt the downward movement of the plunger as the stapler-actuating bar descends. Whenever this occurs there will be no feed of the staple stock wire for formation of a staple, and consequently upon the ensuing operation of the stapler no staple can be driven; the mechanism will simply operate idly.

In the commercial forms of wirebound boxes now on the market, the cleats are usually formed with mortised and tenoned or other mating ends. Cleats of this character are shown in the drawings, having the cutaway or tenoned portions G and shoulders 26 to mate with the correspondingly formed ends of the adjacent cleats.

It is desirable to avoid stapling at the end parts G of the cleats. To avoid stapling at such undesired places or gaps in the work, I provide mechanism automatically controlled by the progression of the work relative to the staplers for interrupting the stapling operation, as for instance by depriving the staplers of staples or staple stock wire by the means previously described, at such times that no staple will be driven when the places referred to are brought to the stapling plane.

The illustrative mechanism for this purpose comprises, alongside each cleat guide, a reciprocating bar 21 which is normally retracted to the position shown in Fig. 1 by a spring 22. Pivoted at 23 upon bar 21

is a spring pressed pawl 24 provided with a finger 25 which normally rides against the moving cleat and drops down into each space G in front of each shoulder 26. As the cleat is driven forwardly through the 70 cleat guide by the preliminary feeding mechanism, pawl 24 will be drawn forwardly with the cleat, as soon as it drops in front of any shoulder 26, and will continue in this forward movement until its end is 75 brought into engagement with a pin 32 which serves to withdraw the pawl from in front of the cleat shoulder 26. As the pawl 24 moves forwardly, drawing bar 21 with it, it operates, through a rod 28 and spring 29, 80 upon the lower end of a lever 31, the upper end of which operates upon swinging bar 15 to throw it beneath head 14' of plunger 14 in the manner already described, so as to prevent stapling action of the stapling 85 mechanism for the short period of time that the space G of each cleat is passing through the stapling plane. The length of time during which the bar 15 is held in its interrupting position may be determined by the compressive length of spring 29. said spring being sufficient to promptly throw lever 31 and, by compression, permitting further movement of bar 21.

In further explanation: As the work advances from the position shown in Fig. 1, the pawl 24 moving along with the cleats will operate through the rod 28 and spring 29 to swing the lever 31 to throw the bar 15 under the head 14' of the staple-wire feed 100 plunger 14. Consequently on the next downward or staple-driving stroke of the stapler, to drive a staple into the cleat ahead of the pawl 24, the plunger 14 will be held, so that there will be no feeding of the staple 105 wire on the return or up stroke of stapler. Further advance of the work brings the pawl 24 into engagement with the throw-out pin 32, allowing release of the interrupting means, and the cleat gap which was engaged by the pawl is brought to the stapling plane. The ensuing down stroke of the stapler will not drive a staple at this place, since there has been an interruption of the staple wire feed just preceding this stroke. 115

Thus the stapling is interrupted at the requisite places by means the actuation of which is controlled by successively presented parts corresponding to such places and moving with the work, the parts referred to in this instance being the cleat shoulders 26; the pawl 24 serving as a detector means to find said parts and to be actuated thereby.

In order to provide a gage stop which will be automatically brought into proper cleat-stopping position at the beginning of the formation of each box blank and thereby to space between blanks, I arrange adjacent each cleat guide, a gage finger 41 which 125

normally rides against one side of the moving cleats. The two fingers 41 are carried by arms 42 secured to a rock shaft 43, each arm 42 being preferably independently angularly adjustable relative to shaft 43 by suitable means, such as temper screws 430, so that the ends of the two fingers 41 may be brought into exact alinement with each other and in parallelism with the stapling plane so as to insure accurate initial positioning of the box blank material. The arms 42 are normally urged to the position shown in Figs. 1 and 2 by a suitable counterweight 42', this weight serving to bring the cam-shaped portions 41' of the fingers 41 into such engagement with pins 32 as to drive the fingers 41 laterally into the cleat guides whenever a space G comes opposite the fingers and thus causing the projection of each finger in front of each cleat shoulder 26. When this action takes place, the fingers 41 will be simultaneously driven along the cleat guides by the moving cleats and, in the absence of any obstruction, will continue such movement until the cam surfaces 41'' of the fingers 41 come into engagement with pins 44, which will cause the fingers 41 to be withdrawn from the cleat guides and returned to normal position by the counterweight 42'. On each return movement of fingers 41 to the position shown in Fig. 1, a finger 45, carried by one of the fingers 41, comes into engagement with a ratchet wheel 46 and advances the same one step. Where the machine is forming box blanks from which to form four-sided boxes, the wheel 46 will be provided with teeth in multiples of four and will be provided with as many pins or shoulders 47 as there are groups of teeth so that, when the final cleats of a blank have engaged fingers 41 and carried the same along the cleat guides and the said fingers have returned to their normal position, the consequent movement of wheel 46 will bring one of the pins 47 into engagement with a finger 48 carried by a locking bar 49 pivoted to swing so that its shoulder 51 may be projected thereby into the path of movement of one of the arms 42. When the projection of shoulder 51 has been accomplished and fingers 41 projected in front of the oncoming initial cleats for a new blank, the fingers 41 will be moved partially along the cleat guides but will be stopped by shoulder 51 at such point that the initial cleats of the new blank will be in proper position to receive their first staples. Fingers 41, when brought to a stop by shoulder 51, form an accurate and rigid gage for the proper placing of the front end of the blank material beneath the stapling mechanism in position to receive the first staple. Before the operator places the sheet material for the new blank, he generally permits the entire machine to come to a stop

and, after placing the sheet material, swings lever 49 to withdraw shoulder 51 from the path of movement of adjacent arm 42, and then starts the machine into operation, as already described.

As represented in Fig. 1, the fingers 41 are shown engaging midway of a series of cleats for a blank, there being two cleats ahead and two behind each of said fingers, and it will be noted that the pins 47 of wheel 46 are in such position that two more steps of wheel 46 will be required before finger 48 is engaged in such a way as to throw stop 51 into active position. Hence, as the parts advance from the position shown, the fingers 41 will be carried along without obstruction until thrown out by engagement of the cams 41'' with pins 44; thereupon the fingers 41 return and the finger 45 turns the ratchet wheel 46 one step. This operation is repeated another time, at which repetition one of the pins 47 will engage finger 48 so as to shift stop 51 to position to obstruct the arm 42 to gage the position of the next blank. At this time the pawl 24 may or may not be in engagement with a cleat shoulder 26, depending upon the lengths of the cleats.

The term stapling-means is used herein to broadly designate any mechanism for connecting the elements of the box-blank together.

I claim as my invention:

1. In a machine for making box-blanks, stapling means, cleat guides extending through the stapling plane, feeding means for driving cleats through said guides, said feeding means comprising a primary feeder and a preliminary feeder, a member arranged adjacent a cleat guide to be engaged intermittently by a cleat and be thereby driven from its normal position, and means controlled by said member in its abnormal position for interrupting the action of the stapling means.

2. In a machine for making box-blanks, stapling means, cleat guides extending through the stapling plane, feeding means for driving cleats through said guides, a member arranged adjacent a cleat guide to be engaged intermittently by a cleat and be thereby driven from its normal position, and means controlled by said member in its abnormal position for interrupting the action of the stapling means.

3. In a machine for making box-blanks, stapling means, cleat guides extending through the stapling plane, a member arranged adjacent a cleat guide to be engaged intermittently by a cleat and be thereby driven from its normal position, and means controlled by said member in its abnormal position for interrupting the action of the stapling means.

4. In a machine for making box-blanks,

stapling means, cleat guides extending through the stapling plane, feeding means for driving cleats through said guides said feeding means comprising a primary feeder 5 and a preliminary feeder, a member arranged adjacent a cleat guide to be engaged intermittently by a cleat and be thereby driven from its normal position, means for intermittently interrupting the action of the 10 stapling means, and a spring connection between said cleat-engaged member and the interrupting means whereby the cleat-engaged member will operate the interrupting means and hold it in operated position during further movement of the cleat-engaged member.

5. In a machine for making box-blanks, stapling means, cleat guides extending through the stapling plane, feeding means 20 for driving cleats through said guides, a member arranged adjacent a cleat guide to be engaged intermittently by a cleat and be thereby driven from its normal position, means for intermittently interrupting the 25 action of the stapling means, and a spring connection between said cleat-engaged member and the interrupting means whereby the cleat-engaged member will operate the interrupting means and hold it in operated position during further movement of the cleat-engaged member.

6. In a machine for making box-blanks, stapling means, cleat guides extending through the stapling plane, a member arranged adjacent a cleat guide to be engaged intermittently by a cleat and be thereby driven from its normal position, means for intermittently interrupting the action of the 35 stapling means, and a spring connection between said cleat-engaged member and the interrupting means whereby the cleat-engaged member will operate the interrupting means and hold it in operated position during further movement of the cleat-engaged member.

7. In a machine for making box-blanks, stapling means, cleat guides extending through the stapling plane, feeding means for driving cleats through said guides said 40 feeding means comprising a primary feeder and a preliminary feeder, a member arranged adjacent a cleat guide to be engaged intermittently by a cleat and be thereby driven from its normal position, means controlled by said member in its abnormal position for interrupting the action of the 45 stapling means, gage fingers adapted to arrest the initial cleats of a blank, and means controlled by the passage of the cleats for holding said gage fingers in gaging position.

8. In a machine for making box-blanks, 50 stapling means, cleat guides extending through the stapling plane, feeding means for driving cleats through said guides said feeding means comprising a primary feeder

and a preliminary feeder, a member arranged adjacent a cleat guide to be engaged intermittently by a cleat and be thereby driven from its normal position, means for intermittently interrupting the action of the 55 stapling means, a spring connection between said cleat-engaged member and the interrupting means whereby the cleat-engaged member will operate the interrupting member and hold it in operated position during further movement of the cleat-engaged member, gage fingers adapted to arrest the initial cleats of a blank, and means controlled by the passage of the cleats for holding said gage fingers in gaging position. 80

9. In a machine for making box-blanks, stapling means, cleat guides extending through the stapling plane, feeding means for driving cleats through said guides said feeding means comprising a primary feeder 85 and a preliminary feeder, a member arranged adjacent a cleat guide to be engaged intermittently by a cleat and be thereby driven from its normal position, means controlled by said member in its abnormal position for interrupting the action of the stapling means, gage fingers arranged adjacent the cleat guides and one of said fingers being movable along the adjacent cleat guide by each passing cleat, means for projecting said fingers intermittently into the cleat guides, and means operated by the movement of the gage finger longitudinally of its cleat guide for intermittently holding the gage fingers to prevent movement of 90 cleats along their guides. 85

10. In a machine for making box-blanks, stapling means, cleat guides extending through the stapling plane, feeding means for driving cleats through said guides said feeding means comprising a primary feeder and a preliminary feeder, a member arranged adjacent a cleat guide to be engaged intermittently by a cleat and be thereby driven from its normal position, means for intermittently interrupting the action of the 105 stapling means, a spring connection between said cleat-engaged member and the interrupting means whereby the cleat-engaged member will operate the interrupting member and hold it in operated position during further movement of the cleat-engaged member, gage fingers arranged adjacent the cleat guides and one of said fingers being movable along the adjacent cleat guide by each passing cleat, means for projecting said fingers intermittently into the cleat guides, and means operated by the movement of the gage finger longitudinally of its cleat guide for intermittently holding the gage fingers 110 to prevent movement of cleats along their guides. 115

11. In a machine for making box-blanks, stapling means, cleat guides extending through the stapling plane, feeding means 120

for driving cleats through said guides said feeding means comprising a primary feeder and a preliminary feeder, a member arranged adjacent a cleat guide to be engaged 5 intermittently by a cleat and be thereby driven from its normal position, means controlled by said member in its abnormal position for interrupting the action of the stapling means, gage fingers arranged adjacent 10 the cleat guides and each projectable into and drivable along the cleat guides by the cleats, means for projecting said fingers in front of each passing cleat, a stop for arresting movement of the gage fingers 15 along the cleat guides, and means controlled by movement of a gage finger along its cleat guide for intermittently driving said stop into stopping position.

12. In a machine for making box-blanks, 20 stapling means, cleat guides extending through the stapling plane, feeding means for driving cleats through said guides said feeding means comprising a primary feeder and a preliminary feeder, a member arranged adjacent a cleat guide to be engaged 25 intermittently by a cleat and be thereby driven from its normal position, means for intermittently interrupting the action of the stapling means, a spring connection between 30 said cleat-engaged member and the interrupting means whereby the cleat-engaged member will operate the interrupting member and hold it in operated position during further movement of the cleat-engaged member, 35 gage fingers arranged adjacent the cleat guides and each projectable into and drivable along the cleat guides by the cleats, means for projecting said fingers in front of each passing cleat, a stop for arresting movement 40 of the gage fingers along the cleat guides, and means controlled by movement of a gage finger along its cleat guide for intermittently driving said stop into stopping position.

45 13. A box blank machine comprising a stapling mechanism having a wire feed, and means for automatically rendering said wire feed inoperative, to prevent the driving of staples without stopping the operation 50 of the stapling mechanism, including an element which engages the cleats and is operated thereby to govern the operation of said means.

14. A box blank machine comprising 55 instrumentalities for feeding materials and inserting fastening devices therein, and means for automatically interrupting the driving of the fastening devices, without stopping the machine, including an element 60 which directly engages the materials and operates to govern the operation of said means, said element being operated a plurality of times for each blank.

15. A machine for stapling suitably 65 prepared materials together to form blanks for

the sides of boxes or crates, comprising endless traveling means for feeding the blank materials, a stapler, a staple wire feed mechanism for said stapler, and means governed by the traveling motion of the feeding 70 means for automatically tripping out the said mechanism between blanks, without interrupting the reciprocation of said stapler, said means including a controller therefor arranged to be engaged by the materials. 75

16. A machine for stapling suitably prepared materials together to form blanks for the sides of boxes or crates, comprising endless traveling means for feeding the blank materials, a stapler, a staple wire feed 80 mechanism for said stapler, and means governed by the traveling motion of the feeding means for automatically tripping out the said mechanism between blanks, without interrupting the reciprocation of said stapler, 85 said means comprising a device that bears on the moving work, and means whereby the said device moves inward between blanks.

17. A machine for stapling suitably prepared materials together to form blanks for 90 the sides of boxes or crates, comprising endless traveling means for feeding the blank materials, a stapler, a staple wire feed mechanism for said stapler, and means governed by the traveling motion of the feeding 95 means for automatically tripping out the said mechanism between blanks, without interrupting the reciprocation of said stapler, said means comprising a member pivoted to drag on the work, a movable member to 100 trip out the wire feed mechanism, and a link connecting said movable member with the said member dragging on the work.

18. A machine for stapling suitably prepared materials together to form blanks for 105 the sides of boxes or crates, comprising endless traveling means for feeding the blank materials, a stapler, a staple wire feed mechanism for said stapler; and means governed by the traveling motion of the 110 feeding means for automatically tripping out the said mechanism between blanks, without interrupting the reciprocation of said stapler, said means comprising a floating element bearing on the moving work. 115

19. A box blank machine comprising instrumentalities for feeding materials and inserting fastening devices therein, and means for automatically spacing between blanks, including an element requiring as many actuations thereof as there are successive sections in the blank in order to cause the spacing operation of said means. 120

20. A machine for construction box-blanks from a plurality of units comprising 125 a stapler provided with a device for feeding the staple wire thereto, means to feed the blank materials forward, an element arranged to bear directly against the passing materials, and means operated by said ele- 130

- ment to interrupt the operation of said device upon the passage of the completed blank.
21. A machine for constructing box-blanks from a plurality of units comprising a device for operating on wire, means to feed the blank materials forward, an element arranged to bear directly against the passing materials, and means operated by said element to interrupt the operation of said device upon the passage of the completed blank.
22. A machine for constructing box-blanks from a plurality of units comprising a stapler provided with a device for feeding the staple wire thereto, means to feed the blank materials forward, an element arranged to bear directly against the passing materials, and means operated by said element to interrupt the operation of said device upon the passage of the completed blank, said element being movable into and out of the path of the moving materials.
23. A machine for constructing box-blanks from a plurality of units comprising a device for operating on wire, means to feed the blank materials forward, an element arranged to bear directly against the passing materials, and means operated by said element to interrupt the operation of said device upon the passage of the completed blank, said element being movable into and out of the path of the moving materials.
24. A machine for constructing box-blanks from a plurality of units comprising a stapler provided with a device for feeding the staple wire thereto, means to feed the blank materials forward, an element arranged to bear directly against the passing materials, and means operated by said element to interrupt the operation of said device upon the passage of the completed blank, said element operating a plurality of times for each blank.
25. A machine for constructing box-blanks from a plurality of units comprising a device for operating on wire, means to feed the blank materials forward, an element arranged to bear directly against the passing materials, and means operated by said element to interrupt the operation of said device upon the passage of the completed blank, said element operating a plurality of times for each blank.
26. A machine for constructing box-blanks from a plurality of units comprising a stapler provided with a device for feeding the staple wire thereto, means to feed the blank materials forward, an element arranged to bear directly against the passing materials, and means operated by said element to interrupt the operation of said device, upon the passage of the completed blank, said element being arranged to operate in the horizontal plane of the blank and at one side thereof.
27. A box blank machine comprising, in combination, fastener-setting mechanism; means for feeding cleats in succession past said mechanism; a member arranged in proximity to the path of movement of the cleats adapted to be engaged intermittently by a cleat and to be displaced thereby from a normal position; and fastener-setting interrupting means controlled by said member in its abnormal position.
28. A box blank machine comprising, in combination, fastener-setting mechanism; means for feeding cleats in succession past said mechanism; a member arranged in proximity to the path of movement of the cleats adapted to be engaged intermittently by a cleat and to be displaced thereby from a normal position; fastener-setting interrupting means; and a spring connection between said member and interrupting means whereby the latter is operated and held in operative position by the cleat-impelled movement of said member.
29. A box blank machine comprising, in combination, fastener-setting mechanism; means for feeding cleats in succession past said mechanism; a member arranged in proximity to the path of movement of the cleats adapted to be engaged intermittently by a cleat and to be displaced thereby from a normal position; and fastener-setting interrupting means controlled by said member in its abnormal position; gage means to arrest the initial cleats of a blank; and means controlled by the passage of the cleats for holding said gage means in gaging position.
30. A machine for use in making wire-bound and cleat-reinforced boxes comprising, in combination, means for supporting assembled box materials including spaced parts during progressive fastening of binding wire to the materials; fastener-setting mechanism to fasten the binding wire to the materials; means to cause relative progression between the assembled materials and fastener-setting mechanism; and progression-controlled fastener-setting interrupting means, including a controller therefor arranged to be engaged by the materials, and to prevent the driving of fasteners at the spaces between said parts.
31. A machine for use in making wire-bound and cleat-reinforced boxes comprising, in combination, means for supporting assembled box materials including spaced parts, during progressive fastening of binding wire to the materials; fastener-setting mechanism to fasten the binding wire to the materials; means to cause relative progression between the assembled materials and fastener-setting mechanism; and progression-controlled fastener-setting interrupt-

ing means, and actuating-means therefor including a member adapted to bear on and be operated by the space-defining parts of the materials.

- 5 32. A box blank machine comprising, in combination, means for supporting assembled box materials including cleats during progressive fastening of binding wire to the materials; fastener-setting mechanism to
10 fasten the binding wire to the materials; means to cause relative progression between the assembled materials and fastener-setting

mechanism; fastener - setting interrupting means; and means for actuating said interrupting means from the work, including a 15 member bodily displaceable by the work.

In witness whereof, I, have hereunto set my hand and seal at Indianapolis, Indiana, this 13th day of November, A. D., one thousand nine hundred and eleven.

JASON H. GREENSTREET. [L. S.]
